UNITED STATES PATENT OFFICE.

PHILIP KURTZ, OF PHILADELPHIA, PENNSYLVANIA.

DESIGN FOR A SWITCHBOARD.

53,180.

Specification for Design.

Patented Apr. 8, 1919.

Application filed October 19, 1916. Serial No. 126,615. Term of patent 7 years.

To all whom it may concern:

Be it known that I, PHILIP KURTZ, a citizen of the United States, residing at Philadelphia, in the county of Philadelphia and State of Pennsylvania, have invented a new, original, and ornamental Design for Switchboards, of which the following is a specification, reference being had to the accompanying drawing, forming a part thereof.

The figure is a front elevation of a switchboard showing my new design.

I claim:

The ornamental design for a switchboard as shown.

PHILIP KURTZ.
